METHOD OF HEAT-TREATING A METALLIC ANNULUS

Homer L. Mueller, Cleveland, Ohio, assignor to
The Cleveland Welding Company, Cleveland,
Ohio, a corporation of Ohio

Application November 2, 1942, Serial No. 464,185

1. Claim. (Cl. 148—13)

1

This invention relates as indicated to a method of heat treating and more particularly to the method of heat treating annular articles such as large rings, flanges and the like.

An expedient way in which large annular articles, such as those having a comparatively large diameter and a relatively small cross-section, may be manufactured is to circularize a flat blank having the desired cross-section and then butt weld the ends together to form the complete annulus. The forming operation incidental to circularizing a flat blank, and the local heating of the annulus in butt welding the ends together, makes it necessary and desirable to heat treat the finished annulus for the purpose of relieving the stresses and strains therein set up by the above named processing steps.

It is also frequently necessary to heat treat for the purpose of hardening a metallic annulus, this form of heat treatment requiring a heating to a hardening temperature, promptly followed by a quench, which is in turn followed by a reheating to a drawing temperature.

When the annulus has a relatively large diameter and a relatively thin cross-section, many problems are encountered in the heat treating process, whether the same be for either or both of the above mentioned purposes. In the first place, it is extremely difficult and expensive to so support this type of object in order that it may not sag and warp during the heat treating operation. A furnace large enough to accommodate such objects becomes uneconomical to operate in view of the proportional relationship between the cubic content of the furnace and the mass of the article.

It is a principal object of my invention, therefore, to provide an improved process for the heat treatment of annular objects of the character and for the purposes above explained, which process affords an easy and economical solution to the problems above pointed out which have attended the prior art practices.

Other objects of my invention will appear as the description proceeds.

To the accomplishment of the foregoing and related ends, said invention then comprises the features hereinafter fully described and particularly pointed out in the claims, the following description and the annexed drawing setting forth in detail certain illustrative embodiments of the invention, these being indicative, however, of but a few of the various ways in which the principle of the invention may be employed.

In said annexed drawing—

2

Fig. 1 is a perspective of an annulus which may be formed by circularizing and butt welding a blank such as that illustrated in Fig. 1;

Fig. 2 is a side elevational view, partially in section, of one form of apparatus which may be employed for the purpose of carrying out the improved process comprising my invention; and

Fig. 3 is a transverse sectional view of a portion of the apparatus illustrated in Fig. 2, taken on a plane substantially indicated by the line 4—4.

The blank is circularized in suitable rolling equipment, and the ends of the blank are welded together as at 2 to form the annulus generally indicated at 3 in Fig. 1. The process comprising my invention is designed for the purpose of quickly and economically heat treating the annulus 3 in order to remove any work strains which may be present therein, and also, if desired, to impart the desired degree of hardness and ductility to the annulus by a progressive heating to a hardening temperature; a quenching; and subsequent heating to a drawing temperature.

One means for carrying out such improved process is illustrated in Fig. 2, wherein a quench tank is generally indicated at 4, and which will be filled to a suitable level, such as indicated by the line 5, with an appropriate quenching medium such as water. A brace 6 is mounted across the tank 4 and it carries a standard 7 on which are rotatably supported a pair of rolls 8. A plurality of paired rolls 9 and 10 are arranged in the tank 4, preferably beneath the level of the quenching medium therein, and all of these circumferentially spaced pairs of rollers are so arranged that when the annulus is placed thereon, the rollers will maintain the annulus in a true circle. One of these pairs of rollers, such as the pair 8, may be provided with a suitable driving pulley (not shown) on the axle thereof, about which may be trained a driving belt 11 for the purpose of driving the rollers and accordingly rotating the annulus in the rollers.

Mounted on a bracket 12, carried by the tank 4, is a small furnace 13, through which the annulus passes as it is rotated by the supporting rollers. This furnace 13, as most clearly illustrated in Fig. 3, comprises two substantially similar sections 14 and 15 hinged together as at 16 and maintained in assembled relation by a latch or detent 17. The furnace 13 comprises a refractory lining 18 and a metallic carrying and supporting shell 19.

The wall of the furnace is perforated at spaced points to accommodate burner nozzles 20. The

arrangement and location of the burners, and the number of the burners used, will be governed by factors such as the size and shape of the cross-section of the annulus; the speed at which the annulus is to be moved through the furnace, etc.

It has been found that while satisfactory results may be achieved by using a few burners of a high heat content gas, such as acetylene, nevertheless, for most purposes best results will be secured by using a fuel, such as natural gas and by arranging the burners in such a fashion that the refractory lining of the furnace becomes very highly heated. In this way the annulus in passing through the furnace derives its heat not only from direct impingement thereon of the flame, but also by radiation from the walls of the furnace. This type of heating produces superior results because of its more even distribution and accordingly the more even heating of the annulus section as it passes through the furnace.

As previously indicated, the furnace is made sectional so that one section may be swung aside to open up the front face of the furnace in order to receive and permit the removal therefrom of an annulus placed on and taken off from the paired guide rollers.

When the annulus is to be hardened, the temperature of the furnace will be so correlated with the speed of travel of the annulus therethrough that the temperature of the annulus section, when it reaches the quenching bath, will be at the proper quenching temperature for the desired hardness. These are all factors which may be readily determined and which are largely dependent upon the character of the particular annulus being treated so that a further and more detailed description is believed unnecessary.

In connection with the hardening operation it is generally customary to reheat the article to a "drawing" temperature, and this may be conveniently accomplished by mounting a second furnace 21 on a bracket 22 on the side of the tank 4 opposite the principal heating furnace 13. The furnace 21 will be similar in construction, although usually smaller than the furnace 13, since the drawing temperature is never as high as the quenching temperature. Otherwise the furnace 21, in its construction and mode of operation, may be similar to the furnace 13 as above described.

From the foregoing description, it will be observed that I have provided an improved process for the economical and expeditious heat treatment of large annular objects which could only

be handled with great difficulty in conventional heat treating furnaces. Moreover, the cost of operation is considerably less than with the prior art practices, due to many factors which will be apparent to those skilled in the art.

Instead of employing a furnace such as 13, I may resort to other expedients for the purpose of heating to a quenching temperature the circumferentially progressive local area of the annulus just prior to its entry into the quenching bath.

Similar alternative provisions may be made for heating the annulus after it has emerged from the quench to a drawing temperature. Since the drawing temperature is, as indicated above, never as high as the quenching temperature, it will be found that, for certain types of annulus sections, entirely satisfactory results may be attained by the use of an open flame heater.

20 Other modes of applying the principle of my invention may be employed, change being made as regards the details described, provided the features stated in the following claim or the equivalent of such be employed.

25 I, therefore, particularly point out and distinctly claim as my invention:

In the manufacture of a metallic annulus, rotatably supporting the annulus on its inner periphery at a plurality of circumferentially spaced 30 locations to maintain the annulus as a true circle, and heating simultaneously from within and without to a substantially uniform degree throughout its cross section a circumferentially progressing local segment of such annulus by 35 radiant heat and flame together.
